UNITED STATES PATENT OFFICE

2,001,413

VACUUM TUBE OSCILLATOR

Paul O. Farnham, Eeenton, N. J., assignor, by
mesne assignments, to Radio Corporation of
America, New York, N. Y., a corporation of
Delaware

Application February 16, 1932, Serial No. 593,335

7 Claims. (Cl. 250—36)

This invention relates to vacuum tube oscillators and particularly to oscillators, and superheterodyne receivers including oscillators, adapted to be tuned over a plurality of frequency bands.

5 In multi-range oscillators of the type including a tapped inductance and a tuning condenser, no difficulty is experienced in maintaining oscillation over two or three adjacent frequency bands but the problem of insuring oscillation becomes
10 increasingly difficult when additional taps are provided in an attempt to cover more frequency bands. Some of the known types of circuits will oscillate freely over the higher frequency band but will not oscillate satisfactorily, if at all, at substantially lower frequencies. Similarly, other systems will oscillate freely at low frequencies but will not operate satisfactorily at higher frequency bands.

This problem of maintaining oscillation of a 20 plurality of frequency bands is encountered, for example, in the construction of multi-range superheterodynes of the type in which tapped inductances are employed in the oscillator, the carrier frequency and the intermediate frequency circuits to provide a different intermediate frequency for each carrier frequency band. The invention will be described as embodied in such a multirange superheterodyne (described and claimed in my Patent No. 1,943,788, dated Jan. 16, 30 1934 and assigned to the same assignee as the present application), but it will be apparent that the novel oscillator system may be employed in other types of circuits or as an oscillation generator of general application.

35 An object of the invention is to provide an improved multi-range oscillator of the type including a resonant circuit comprising a tapped inductance and a tuning condenser, the oscillator circuits being so arranged that the change from one tuning range to another requires no adjustment additional to the selection of the appropriate inductance tap. A further object of the invention is to provide a multi-range tuned oscillator in which the normal coupling between the 45 circuits of the oscillator tube is automatically supplemented by an additional coupling when the oscillator is adjusted for operation at that end of the frequency range at which the normal coupling is not sufficient to maintain oscillation. More specifically, an object is to provide a multi-range oscillator in which the plate circuit of the tube is coupled to a portion of the capacity included in the resonant circuit, and in which fixed circuit elements provide an inductive coupling 50 between the plate and resonant circuits when the

oscillator is adjusted for operation at its higher frequency ranges, the coupling effect of the fixed circuit elements being negligible when the oscillator is adjusted for operation within its lower frequency ranges. Further specific objects relate to the provision of multi-range superheterodyne receivers including multi-range oscillators capable of maintaining oscillation over an extended range of frequencies.

These and other objects and advantages of the 10 invention will be apparent from the following specification when taken with the accompanying drawing in which the single figure is a fragmentary circuit diagram of a superheterodyne receiver embodying the invention.

15 In the drawing, the reference numeral 1 identifies a carrier wave amplifier tube which receives signal energy from a collector structure 2 of any desired form. The amplified signal energy from tube 1 is transmitted to a first detector tube 3 20 where it beats with locally generated oscillations from the oscillator tube 4 to produce a modulated signal of intermediate frequency which is impressed upon an intermediate frequency amplifier tube 5. This will be recognized as a conventional arrangement of coupled tube circuits in a superheterodyne receiver and one which may be varied, in accordance with the particular design requirements, by the introduction of additional carrier wave and/or intermediate frequency 30 amplifier stages.

25 In accordance with the present invention, the oscillator system is so constructed that oscillations will be maintained over an extended range of frequencies. The adjustment of the superheterodyne for the reception of signals in different carrier frequency bands is obtained by changing the effective inductance of the resonant 35 circuits of the receiver.

The magnitudes of the inductances included in 40 the resonant circuits of these several types of stages may be varied by the use of interchangeable coils or by tapped coils and switches. For purposes of illustration, tapped coils and switches are shown and, for this particular type of adjustable inductance, the coils preferably take the form described and claimed in the copending application of W. D. Loughlin and Paul O. Farnham, Ser. No. 563,180, filed Sept. 16, 1931, issued as Patent No. 1,989,205, dated Jan. 29, 1935 and 45 assigned to the same assignee as the present application.

45 The input circuit of the carrier wave amplifier tube 1 is shown as including a tapped inductance L shunted by a tuning condenser C, the switch 50

for varying the effective inductance of coil L including a contact arm 6 for progressively grounding and short circuiting sections of coil L as the switch is manipulated to adapt the receiver for the reception of signals in progressively higher frequency bands, as explained in detail in the last minute patent. The coupling between the first detector tube 3 and the preceding carrier wave amplifier stage may take the form of a transformer having a secondary substantially identical with the described tapped inductance L and switch arm 6, the primary winding L₁ of the transformer being wound turn for turn with its secondary or the inductance L and included, as is customary, in the plate circuit of the last carrier wave amplifier stage. The high potential terminals of the transformer are connected by a condenser C₁ to reduce the effective resistance of the secondary winding when a portion of the winding is short-circuited.

The coupling between the first detector 3 and the first intermediate frequency amplifier 5 may be of the auto-transformer or tuned impedance type and is illustrated as including a tapped inductance L₂ in the plate circuit of the detector; a switch arm 7 being provided for adjusting the effective impedance of the inductance L₂ that is shunted by the trimming condenser 8. As indicated by the broken lines 9 connecting the several switch arms 6 and switch arm 7, the switch arms are preferably connected mechanically for simultaneous adjustment.

With tuned carrier wave and intermediate frequency circuits of the described types, it will be apparent that the oscillator 4 must be operated over different frequency bands in accordance with the particular frequency band in which the desired signal frequency is to be found. As illustrated, the circuit network of the oscillator tube 4 has a tuned grid circuit comprising a tapped inductance L₄, a series lagging condenser C_s, a tuning condenser C which is mechanically connected, as indicated by broken lines 11, to the condensers C employed for tuning the carrier frequency circuits, and a small condenser C₂ in shunt with the tuning condenser C. The switch arm 12 which controls the effective magnitude of the inductance L₄ is preferably mechanically connected, as indicated by broken line 13, to the common operator 9 of the switches 6 and 7 of the carrier and intermediate frequency circuits. As the gang condenser is adjusted for tuning, the presence of the series condenser in the tuned circuit of the oscillator makes the value of the total capacity tuning the oscillator coil lag behind the value of the capacity tuning the radio frequency circuits, and the series condenser which thus makes it possible to employ a single tuning control in super-heterodyne receivers will therefore be designated, in the following specification and claims, as the "lagging condenser". This will be recognized as one of the known arrangements for tracking the carrier and oscillator circuits to maintain a constant frequency difference between the resonant frequencies of the circuits which are simultaneously tuned by a gang condenser, but it will be apparent that other known methods of maintaining tracking may be employed.

The oscillator is of the general type described and claimed in my copending application Ser. No. 585,592, filed Jan. 8, 1932, the plate circuit being coupled across the series lagging condenser C_s by a condenser C₃, the lead to the source of plate current supply including a choke 14 which has sufficient impedance to maintain the oscillatory

potential on the plate of tube 4 substantially the same as that of the junction of condenser C_s and inductance L₄. A grid leak resistance R is connected between the grid and cathode to determine the direct current potential of the grid.

The oscillatory voltage developed by tube 4 is impressed on the first detector tube 3 by connecting the plate of tube 4 to the cathode of tube 3 through the blocking condenser 15. The cathode of the detector tube 3 is connected to ground through parallel paths provided, respectively, by a condenser 16 and a serially connected choke 17 and bias resistor 18. The choke 17 is included to prevent the resistor 18 from varying the effective ratio of the impedances of condensers 15 and 16 as the receiver is tuned over a wide range of frequencies.

So far as described, the oscillator circuit is constructed in accordance with the disclosure of my just mentioned patent and will function efficiently over a plurality of frequency bands and, as described therein, the oscillatory voltage developed in any one frequency band will increase with decreasing frequency. When, as illustrated, the several inductances are tapped to permit tuning over five different frequency bands, it is difficult or impossible to construct an oscillator network which will provide sufficient coupling to insure oscillation at the highest or two higher frequency ranges. In accordance with this invention, the normal coupling between the plate and tuned circuits which provides for oscillation in the lower frequency bands is supplemented by an inductive coupling M which becomes effective only when the switching system is adjusted for tuning the oscillator of its highest or two higher frequency bands. This inductive coupling is provided by the inclusion in the plate circuit of a few turns L₅ which are coupled to the highest frequency section L_{4a} of the tapped inductance L₄, the sense of the coupling being such as to increase the coupling between the plate circuit and the tuned grid circuit.

Within all frequency ranges except the highest range or the two higher ranges, the ratio of the turns of inductance L₅ to the effective turns of the inductance L₄ is so small that the inductive coupling between the plate and grid circuits is negligible. However, the adjustment of the switching system to short circuit all but the highest frequency section of coil L₄ automatically provides the additional coupling which is required for maintaining oscillation over the highest band of frequencies. In one embodiment of the invention, the oscillator was designed to operate over a frequency range of from 225 to 24,000 kilocycles and the two higher frequency bands extended from 4,000 to 9,000 and from 10,000 to 24,000 kilocycles, respectively. The high frequency section L_{4a} of the oscillator inductance L₄ was a solenoid winding of four turns and the inductance L₅ was a winding of two turns. The supplemental coupling introduced at the higher frequency ranges insured oscillation over the highest frequency range and the high frequency end of the next lower frequency range.

It will be apparent that the invention is not limited to the particular circuit illustrated in the drawing as other arrangements for automatically introducing an additional coupling at one end of the frequency range of a multi-range oscillator will be apparent to those familiar with the design and construction of oscillator circuits.

I claim:

1. In an oscillator, the combination with a

tube having plate and grid elements cooperating with a cathode; of a circuit between the cathode and one of said elements; said circuit including circuit elements having reactances of opposite types, means for adjusting the effective magnitude of one type of reactive circuit element to tune the circuit over a frequency band, and means for varying the effective magnitude of a circuit element having reactance of the opposite type to adapt the circuit for tuning over different frequency bands; a circuit between said cathode and the other element, said second circuit being coupled across a portion of one of said types of reactive circuit elements, and fixed means providing a supplemental coupling between said circuits which becomes automatically more effective when the effective magnitude of said circuit element having reactance of the opposite sign is varied to one limit of its range of variation in magnitude.

2. In an oscillator, a tuned circuit including a tapped inductance and a tuning condenser, a second circuit capacitively coupled to said tuned circuit, and means operative only when the tapped inductance is adjusted for resonating at the highest frequency bands to provide a second coupling of substantial magnitude for supplementing said first coupling.

3. In an oscillator, the combination with a vacuum tube having plate and grid elements cooperating with a cathode; a resonant circuit between cathode and grid comprising a tapped inductance, a series lagging condenser and a tuning condenser, the junction of said condensers being connected to the cathode; and means coupling the plate circuit across the series lagging condenser; of a coil in the plate circuit and coupled to the section of said tapped inductance adjacent the grid.

4. In a multi-range superheterodyne receiver, an oscillator comprising a tube, a tuned circuit including a tapped inductance and a tuning condenser, a second oscillator circuit capacitively coupled to said tuned circuit, and fixed means

automatically providing a second coupling between said circuits which becomes automatically more effective when the tapped inductance is adjusted for operation over its highest frequency range.

5. An oscillator of the type adapted to be tuned over a plurality of frequency bands and having a tuning condenser cooperating with an inductance divided into sections by a plurality of taps, means for progressively short circuiting any desired number of sections of said inductance except that terminal section which is resonated over the highest frequency band by the tuning condenser, and a second circuit capacitively coupled to the tuned circuit comprising the tuning condenser and tapped inductance, said second circuit including an inductance coupled to the said terminal section of the tapped inductance.

6. An oscillator as claimed in claim 5, wherein said tuned circuit includes a relatively fixed condenser in series with said tuning condenser and tapped inductance, and said second circuit is coupled across said fixed condenser.

7. In a vacuum tube oscillator of a type including a pair of circuits, reactive means providing coupling between said circuits and supplemental means supplying additional coupling between said circuits, one of said circuits having a reactive circuit element adjustable in discrete steps to adapt the oscillator for tuning over a plurality of frequency ranges, the method of producing sustained oscillations in certain of said frequency ranges within which the reactive means is not operative to sustain oscillations, which method comprises increasing the energy feed-back through said supplemental coupling means when said oscillator is adjusted to permit operation within said certain frequency ranges, and automatically decreasing the energy feed-back through said supplemental coupling means to a negligible quantity when said oscillator is adjusted to permit operation in other frequency ranges.
